Patented Apr. 11, 1922.

UNITED STATES PATENT OFFICE.

JAMES H. NELSON, OF KANSAS CITY, MISSOURI.

TOY SHOOTING GALLERY.

1,412,625.

Specification of Letters Patent. Patented Apr. 11, 1922.

Application filed November 5, 1920. Serial No. 421,901.

To all whom it may concern:

Be it known that I, JAMES H. NELSON, a citizen of the United States, residing at Kansas City, in the county of Jackson and 5 State of Missouri, have invented certain new and useful Improvements in Toy Shooting Galleries; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specifica- 15 tion.

This invention relates to a toy shooting gallery and one of the objects thereof is to provide a shooting gallery provided with a projectile impeller which is adapted to be 20 readily manipulated, particularly by juveniles, for directing a projectile against an object or objects. The invention contemplates a gallery structure in which a projectile impeller is associated therewith, 25 gallery and the projectile impeller or gun being permanently attached one to the other in such a manner that the impeller muzzle may be elevated for trajectory or swung laterally for terrain.

30 Means is also provided for utilizing a single shot or projectile again and again in the gun, this being possible by the construction of the gallery and gun mounting which insures a return of the projectile back into 35 the breech of the gun, ready to be fired after each discharge.

In other words, the gun is self-loading due to the fact that the projectile gravitates back into the breech ready to be fired after 40 it has struck against the end of the gallery. This is an important feature of my invention as it always insures the gun being loaded ready to be fired by setting the hammer and pulling the trigger.

45 I may utilize swinging manikins or toy objects for the targets against which the projectile is to be fired, or a bull's eye may be associated therewith or substituted therefor at the whim of the user.

50 I have also provided means for setting up the movable targets after they have been knocked down by the projectile.

There are other novel features of the invention of more or less importance which 55 will be referred to hereinafter and which

will be apparent by reference to the accompanying drawings, in which—

Fig. 1 is a perspective view of a gallery constructed in accordance with my invention.

Fig. 2 is a vertical, longitudinal, sectional view through the projectile impeller or gun.

Fig. 3 is a top view of the stock of the gun showing the runway for the return of the projectile in elevation, and

Fig. 4 is a bottom plan view showing the connecting plate between the gun base and the gallery structure.

The gallery per se may consist of a trough-shaped structure 1 having diverging sides 2 and 3 and a back 4. The sides are raised at their rear portions and support a transparent cover 5, which may extend any distance toward the forward edge of the gallery to protect the targets and prevent the projectile from escaping after it has been discharged from its gun.

Suitable targets are enclosed within the space formed by the sides, ends and cover 5 and for the purpose of illustration I have shown a plurality of manikins 6, mounted upon a shaft 7 and having depending projections 8 constituting braces to support them when they are in an upright position.

The manikins are loosely mounted upon 85 the shaft 7 so that when the shot strikes one of them above the shaft 7, it will be knocked down. A crank shaft 9 in the sides 2 and 3 in rear of the manikins, however, is adapted to be swung in an obvious manner to reset the targets.

The gallery constitutes a runway, at the forward end of which is the gun, mounted upon a base 10 and consisting of a tube 11 having a breech 12 with an inlet opening 13 95 at its side adjacent to the return-way 14, which communicates with the runway of the gallery.

The side opposite the opening 13 is solid so that the projectile must pass against the 100 shoulder 15 and enter the inclined return runway 14 and pass into the breech.

The firing element or flap 16, covering the breech 12, may be held to the gun by any suitable means, as by a fastening device 17, 105 and immediately in rear of the gun breech is a hammer 18 pivoted at its lower end on a pivot 19 secured to the stock 20, fastened to the gun base 10. The hammer is connected to a cock spring 21 provided with a shoul-

der 22 and connected at one end to a coil spring 23, the other end of the coil spring being fastened to the stock as at 24, Fig. 2.

The normal tendency of the spring just described will be to throw the hammer 18 against the firing member 16. This will be prevented, however, when the hammer is cocked by the engagement of the shoulder 22 with the detent or pin 25. The cam trigger 26 is pivoted to the stock as at 27 and is adapted to move the spring member 21 off its detent when the trigger is pulled back so that the spring 23 may snap the hammer against the impeller element 16 to project the projectile 27 against the object at which it is aimed.

The base of the gun may be secured to the bottom of the gallery by a flexible plate 28. This plate preferably consists of a steel or some spring material having one end, as at 29, fastened by a plurality of fastening devices and the other end pivotally secured, as at 30, so that the base may be swung from right to left to afford the proper terrain in sighting the gun along a horizontal line, the flexibility of the plate 28 permitting the muzzle of the gun to be raised and lowered for trajectory. Therefore, every possible point on the back 4 may be aimed at by manipulating the gun through the stock and base.

When the target is sighted and the trigger is pulled, the projectile will be forced against

the manikin or toy target, rebounding back to the trough or alley 14 where it will enter the breech of the gun through the port 13, ready to again be fired when the hammer is pulled back to the position shown in Fig. 2 and the trigger operated in the usual manner.

From the foregoing it will be apparent that the device is always ready for use and that the projectile can be used over and over again because it will automatically return to the breech of the gun every time it is fired.

What I claim and desire to secure by Letters-Patent is:

In combination with a troughed gallery element, having an open front end, a gun mounting comprising a base, connected to the gallery element for vertical and lateral adjustment, and having a return runway at one side and a flared shoulder at the front for directing objects from the troughed gallery element into said runway, a gun barrel on said base having a bore opening through both ends and having an opening at its breech connecting the gun bore with said runway, a spring flap at the breech end of the gun bore, a hammer adapted for striking the spring flap, and means for controlling said hammer.

In testimony whereof I affix my signature.

JAMES H. NELSON.
